(57) **CLAIM**

The ornamental design for a transformable block toy, as shown and described.

DESCRIPTION

FIG. 1 is a front view thereof, showing a transformable block toy of my new design;

FIG. 2 is a back view thereof;

FIG. 3 is a right side view thereof;

FIG. 4 is a top plan view thereof;

FIG. 5 is a bottom plan view thereof;

FIG. 6 is an anterior perspective view thereof;

FIG. 7 is a posterior perspective view thereof;

FIG. 8 is a front view thereof, showing a folded state of a transformable block toy;

FIG. 9 is a back view thereof;

FIG. 10 is a right side view thereof;

FIG. 11 is a left side view thereof;

FIG. 12 is a top plan view thereof;

FIG. 13 is a bottom plan view thereof;

FIG. 14 is an anterior perspective view thereof; and,

FIG. 15 is a posterior perspective view thereof.

The broken line showing of the transformable block toy is for the purpose of illustrating portions of the article that forms no part of the claimed design.
